UNITED STATES PATENT OFFICE.

ABRAM HALL, OF DENVER, COLORADO.

VALVE FOR RAILWAY AIR-BRAKE SYSTEMS.

1,179,004.

Specification of Letters Patent.

Patented Apr. 11, 1916.

Application filed November 3, 1915. Serial No. 59,347.

To all whom it may concern:

Be it known that I, ABRAM HALL, a citizen of the United States, residing at Denver, in the county of Denver and State of Colorado, have invented certain new and useful Improvements in Valves for Railway Air-Brake Systems, of which the following is a specification.

My invention relates to a detachable emergency valve for railway air-brake systems, its primary object being to provide a valve adapted for connection with a member of the hose or pipe couplings ordinarily used in railway air-brake systems, and provided with means for its adjustment from a remote point on a railway car to which it is applied.

Another object of my invention is to provide in connection with a valve of the character specified, a signal which is sounded by air escaping from the brake system when the valve is adjusted to a determined position.

It is well known to those skilled in the art to which this invention relates, that in making up a train of railway cars, a valve is connected in the air-brake system at the rear end of the train to be used in emergency for the application of the brakes, independent of the brake-controlling mechanism on the engine.

This valve as used at present is attached at the end of a hose which carries at its opposite end one of the members of the hose couplings commonly used in railway air-brake systems.

The coupling-member of the hose is attached to its correlative at the end of the train pipe of the system and the end of the hose at which the valve is attached is by any suitable means fastened to the platform railing of a passenger car or at the top of a box car, as the case may be. It will be readily seen that this arrangement is disadvantageous especially in that different lengths of hose are required for the application of the valve to railway cars of different constructions and that specially designed fastening means are necessary to secure the hose in a position in which the valve at its end is within easy reach of the brakeman.

In the present invention the inconveniences and objections above alluded to are effectively avoided by the provision of a valve which is directly connected with the

coupling member by interlocking engagement with the clamping claws thereof, and which by means of a cord or chain is operated for the exhaust of air from the system, or for sounding a signal as a warning to pedestrians and drivers of vehicles when a train of cars is pushed by the engine.

With the above objects in view, my improved valve consists of the mechanism illustrated in the accompanying drawings in the various views of which like parts are similarly designated, and in which,

Figure 1 is a side view of the end portion of a box-car to which my invention is applied, Fig. 2, an enlarged side elevation of the valve in its operative position with relation to the hose at the end of the train-pipe of an air-brake system, Fig. 3, a section taken along the line 3—3, Fig. 2, and Fig. 4, 75 a transverse section along the line 4—4, Fig. 3.

In the drawings, the reference numeral 2 designates a member of the hose or pipe-coupling ordinarily used in railway air-brake systems, which is attached to a hose 3 connecting with the pipe line of the system at the end of the car.

The coupling member is as usual provided with claws 4 and 5 for its interlocking connection with a complementary member on the train-pipe of an adjoining car and it has a recess 6 to receive an elastic gasket 7 which makes the joint between the members impervious to air.

My improved valve consists of a housing 10 provided with claws 8 and 9 which are the counterpart of those used on the ordinary hose couplings of which the hereinbefore referred to part at the end of the 95 hose 3, is a member.

The housing has a tapering valve seat which at its largest end has an opening in the face of the housing which in practice engages the contact face of the coupling-member. A tapering valve plug 12 seated in the housing has a stem 13 projecting exteriorly of the same for the attachment of an operating lever 14. The lever which is secured to the valve-stem by a pin 15 has a 105 recess for the reception of a coiled spring 16 which by engagement with the outer end of the housing, holds the valve plug in air-tight contact with its seat. The housing has in connection with its tapering seat, a transverse port 17 for the exhaust of air from the air-brake system, and a second port 18

of smaller diameter for the application of a whistle 19.

The valve-plug has a longitudinal chamber 20 which at its largest end is open to communicate with the interior of the coupling member. The plug has furthermore, two transverse ports 21 and 22 which in diameter, correspond respectively with the ports 17 and 18 of the housing. The port 21 being normally out of alinement with the exhaust port 17, is brought in register therewith by a partial rotation of the valve plug, and the smaller port 22 which normally is separated from the port 18 of the whistle 19 is by a different angular movement of the plug brought into communication therewith.

A coiled spring 23 is at its opposite ends attached to the lever 14 and a lug 24 on the valve housing to yieldingly maintain the valve plug in its normal closed position, and a stop 25 on the valve housing is placed with relation to the lever to determine by engagement therewith, the position in which the port 21 of the valve plug registers with the port 17 of the housing for the exhaust of air from the brake system.

In operation, the hose at the end of the pipe-line is bent upwardly as shown in Fig. 1 of the drawings, and the valve is secured to the coupling member at the end of the hose 3 by interlocking engagement of their complementary claws. With the parts in this position, the chamber of the valve-plug is in continuous communication with the interior of the coupling member to admit air to the ports 21 and 22.

The gasket 7 is placed in the annular recess of the coupling section and a thereto opposite recess in the face of the housing to insure an air-tight joint between the parts, and the spring 16 within the recess of the lever provides an air-tight contact of the valve-plug with the seat in the housing.

The spring 23 maintains the valve plug in its normal closed position, and a cord or chain 26 is attached at the end of the valve lever for its operation from a higher point on the car to which the valve is applied.

In Fig. 1 of the drawings, the cord is attached adjacent the running board at the top of a box-car 27 and is thus readily accessible to the brakeman either from the ground or from the top of the car.

To apply the brakes in case of emergency the cord or chain is pulled upwardly until the movement of the valve lever is arrested by its engagement with the stop on the valve-housing when the ports 17 and 21 are in register for the exhaust of air from the air brake system.

In case a train is pushed by the engine the valve may be employed to sound signals as a warning for pedestrians and drivers of vehicles at road crossings, by bringing the

ports 21 and 18 in register and thereby admitting air to the whistle 19.

Having thus described my invention what I claim and desire to secure by Letters Patent is:

1. A valve of the character described comprising a ported housing having claws adapted to coöperate with the claws on a member of a hose- or pipe coupling of a railway air-brake system, for securing the housing to the said member, and a rotary valve-plug seated in the housing, the said valve having a chamber open for connection with the interior of a coupling member to which the housing is attached, and a port adapted to be brought into and out of register with a port in the housing and said housing and the valve plug in its normal position, coöperating to close the air-brake system against the escape of air at the point at which the housing is attached thereto.

2. A valve of the character described comprising a ported housing having claws adapted to coöperate with the claws on a member of a hose- or pipe-coupling of a railway air-brake system, for securing the housing to the said member, a rotary valve-plug seated in the housing, the said valve having a chamber open for connection with the interior of a coupling member to which the housing is attached, and ports adapted to be brought in and out of register with ports in the housing, and said housing and the valve plug in its normal position, co-operating to close the air-brake system against the escape of air at the point at which the housing is attached thereto and an air-actuated signal connected with a port of said housing.

3. A valve of the character described, comprising a ported housing having claws adapted to coöperate with the claws on a member of the hose- or pipe coupling of a railway air-brake system, for securing the housing to the said member, a rotary valve plug seated in the housing, the said valve having a chamber open for connection with the interior of a coupling member to which the housing is attached, and a port adapted to be brought into and out of register with a port in the housing, an operating lever on the valve plug, and a spring yieldingly holding the lever in a position in which the ports of the housing and the plug are out of register.

4. A valve of the character described comprising a ported housing having claws adapted to coöperate with the claws on a member of a hose- or pipe-coupling of a railway air-brake system, for securing the housing to the said member, a rotary valve-plug seated in the housing, the said valve having a chamber open for connection with the interior of a coupling member to which the housing is attached, and a port adapted

35

to be brought into and out of register with a port in the housing, an operating lever on the valve-plug, and a spring in a recess of the said lever in engagement with the housing to hold the valve plug in air-tight contact with its seat.

5. A valve of the character described comprising a ported housing having claws adapted to coöperate with the claws on a member of a hose- or pipe-coupling of a railway air-brake system, for securing the housing to the said member, a rotary valve plug seated in the housing, the said valve having a chamber open for connection with 10 the interior of a coupling member to which the housing is attached, and a port adapted to be brought into and out of register with a port in the housing, an operating lever on 15 the valve plug, a spring yieldingly holding the plug in a position in which the ports of the housing and the plug are out of register and a stop on the housing to determine the 20 position of the lever in which a port in the valve plug is in register with a port of the 25 housing.

6. The combination with a member of a hose or pipe coupling in a railway air-brake system, of a hand-operated valve having integral claws for its rigid and detachable 30 connection therewith and normally closing the system against the escape of air at the point at which it is connected therewith,

the said valve having ports normally out of alignment for the exhaust of air from the system.

7. The combination with a member of a hose or pipe coupling in a railway air-brake system, of a hand-operated valve having integral claws for its rigid and detachable 40 connection therewith and normally closing the system against the escape of air at the point at which it is connected therewith, the said valve having ports normally out of alignment for the exhaust of air from the system, and means for the operation of said 45 valve at a point remote therefrom.

8. The combination with a member of a hose or pipe coupling in a railway air-brake system, of a hand-operated valve having integral claws for its rigid and detachable 50 connection therewith and normally closing the system against the escape of air at the point at which it is connected therewith, the said valve having ports normally out of alignment for the exhaust of air from the 55 system, and an air-actuated signal connected with a port of the valve.

In testimony whereof I have affixed my signature in presence of two witnesses.

ABRAM HALL.
